UNITED STATES PATENT OFFICE.

GEORGE BRADSHAW, OF CHICAGO, ILLINOIS, ASSIGNOR OF ONE-HALF TO
GEORGE W. HOYT, OF SAME PLACE.

GARMENT-FASTENER.

SPECIFICATION forming part of Letters Patent No. 479,163, dated July 19, 1892.

Application filed February 1, 1892. Serial No. 419,922. (No model.)

To all whom it may concern:

Be it known that I, GEORGE BRADSHAW, a citizen of the United States, residing at Chicago, in the county of Cook and State of Illinois, have invented certain new and useful Improvements in Garment-Fasteners; and I do declare the following to be a full, clear, and exact description of the invention, such as will enable others skilled in the art to which it applies to make and use the same, reference being had to the accompanying drawings, and to the letters of reference marked thereon, which form a part of this specification.

Figure 1 represents a perspective view of a garment-fastener embodying my invention. Fig. 2 is a similar view of a modified form of my invention.

My present invention relates to garment fasteners or supporters and to fabric hooks or clasps.

The improvements consist of the following construction and combination of the parts, which will be now particularly described, and the points of novelty then set forth in the claims.

In the drawings, A represents one form of my improved hook. It consists of two wire bars, the ends of which form contiguous hooks, which are adapted to engage the garment.

B is the looped end of the garment-supporter.

C are parallel parts bent at right angles to the loop.

D are the inclined continuations of the wires, which cross each other, as shown, and are further extended parallel with each other at E.

F represent the double - hooked ends of the supporter, and are curved outwardly in the form shown by the drawings. It will be noticed that the ends of the double hooks F are pointed, and that they are not parallel, but approach each other at a converging angle, the points of the hooks lying at the intersection of the angle. The form of the supporter is similar to that of two button-hooks arranged side by side.

The invention may be used for a great variety of purposes—such, for instance, as a stocking-supporter or a skirt or sleeve clasp.

In fact, it may be used in any practicable

manner in connection with apparel or in connection with upholstery decorations or the like.

In Fig. 2 the hooks F of my invention are the same as those shown in Fig. 1; but the continuation of the wires G therefrom do not cross each other, but are arranged substantially parallel, the wires themselves being bent over at an intermediate point H to form a hook I. This form of my invention is designed more particularly as a drawers-supporter for men's use, the hook I being placed over the waistband of the pants and the double hook engaging the cloth of the drawers.

In using my invention as a garment-supporter, or, in fabric generally, the double hook is engaged with the cloth by drawing the same in between the hooks in any suitable manner, the hooks themselves spreading apart by the natural spring or resiliency of the wire. The tendency of the hooks to return to their normal position causes them to engage the cloth, and owing to the peculiar angle at which the hook - points lie any pressure or pull upon the supporter causes the hooks to firmly engage the fabric.

My invention is very simple and very cheap to manufacture. There are no parts to get out of order, and the device can be easily manipulated with one hand, and it is remarkably efficient in operation.

A rearward movement of the supporter along a ridge of the fabric and then a reverse or forward movement cause the supporter to instantly engage the cloth, and this manipulation can be done easily with one hand; in fact, more easily than with two. The converging angles of the double hooks are essential to this efficient operation of my invention. The fabric, after being pierced by the point, is drawn outwardly along the line of the hooks, thereby taking away any fullness of the cloth in the ridge to which the fastener or supporter is engaged.

I claim—

1. The herein-described pin-fastener, consisting of a wire or wires bent into a heart-shaped configuration, at one end having two points the extremities of which lie adjacent to and in the same plane with each other and

95

100

at the other end provided with a resilient connection which permits the points to be sprung apart, substantially as described.

2. The herein-described pin-fastener, consisting of a wire or wires bent into a heart-shaped configuration at one end and a hook at the other, said heart-shaped configuration having two points the extremities of which lie adjacent to and in the same plane with each

other, and a resilient connection between the ends, which permits the said points to be sprung apart.

In testimony whereof I affix my signature in presence of two witnesses.

GEORGE BRADSHAW.
